US0D1067809S

(12) **United States Design Patent** (10) **Patent No.:** **US D1,067,809 S**
(45) **Date of Patent:** **** Mar. 25, 2025**

(54) **COMBINED SETTING AND GEMSTONE**

(71) Applicant: **LOUIS VUITTON MALLETIER**,
Paris (FR)

(72) Inventors: **Francesca Amfitheatrof**, Paris (FR);
Paul Harrison, Paris (FR); **Naomi Brown**, Paris (FR)

(73) Assignee: **Louis Vuitton Malletier**, Paris (FR)

(**) Term: **15 Years**

(21) Appl. No.: **29/859,198**

(22) Filed: **Nov. 8, 2022**

(30) **Foreign Application Priority Data**

May 12, 2022 (FR) 20222134

(51) **LOC (15) Cl.** **11-01**

(52) **U.S. Cl.**
USPC **D11/92**

(57) **CLAIM**

The ornamental design for a combined setting and gemstone, as shown and described.

DESCRIPTION

FIG. 1 is a perspective view of a combined setting and gemstone showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets
